HIGH FREQUENCY ANTENNA WITH LAMINATED REFLECTOR

Norman R. Wild, Hollis, and Robert L. Williston, Milford, N.H., assignors, by mesne assignments, to Sanders Associates, Incorporated, Nashua, N.H., a corporation of Delaware

Filed Jan. 26, 1954, Ser. No. 406,134

4 Claims. (Cl. 343—840)

This invention relates to directive antenna systems for the radiation and reception of high frequency electromagnetic energy waves. More particularly, this invention relates to antennas employing a paraboloid reflector to obtain directivity as used in radar.

In conventional search techniques the antenna is typically oscillated to scan a desired area. The rate of oscillation and the efficiency of radiation has, in the past, been limited by the weight and strength of the paraboloid reflector and the error introduced by deformation of the paraboloid. By increasing the strength to weight ratio of the reflector the oscillation rate can be increased without error due to deformation of the reflector. This is done in the present invention with a composite parabolic structure having wire screening as a reflecting element and a metallic supporting material bound together as an integral one piece structure with a radiator axially secured thereto and held with supporting rods.

It is an object of this invention to provide an improved antenna with a reflector in the form of a precise paraboloid;

It is a further object of this invention to provide an improved antenna with a paraboloid reflector having a mounting surface precisely located with respect to the axis of the paraboloid; and

It is a still further object of this invention to provide an improved antenna with a paraboloid reflector that is strong, light weight, economical to manufacture and will retain its precise construction under extremely adverse environmental conditions.

Other and further objects of this invention will be apparent from the following description of a typical embodiment thereof, taken in connection with the accompanying drawings.

In accordance with this invention there is provided an antenna comprising successive layers of resin impregnated glass cloth and a conductive reflecting member. An antenna carrying metallic supporting web is disposed between the layers and behind the reflecting member and a foam resin is used to bind them all together to form a composite paraboloid reflector. A radiator is centered by the web and mechanically connected thereto by a plurality of supporting rods.

In the accompanying drawings:

Fig. 1 is a three-dimensional perspective view of an antenna embodying this invention;

Fig. 2 is a side view of the antenna of Fig. 1;

Fig. 3 is a three-dimensional perspective view of the paraboloid reflector of the antenna of Fig. 1;

Fig. 4 is an exploded view of the elements of the paraboloid of the antenna of Fig. 1; and

Fig. 5 is an enlarged cross-sectional view of a portion of the antenna, illustrating a supporting rod assembly.

Referring now in more detail to the drawings, in Fig. 1 a radiator 1 is shown mounted on a paraboloid reflector 2. The radiator is supported at one end by mounting cap 3 and support rods 4. The support rods are assembled to the paraboloid reflector 2 at the junctions 5. High

2

frequency energy is coupled through a transmission line 6 which is supported by mounting bracket 7 in contact with the paraboloid reflector 2. Mounting holes 8 permit assembly of the antenna to a supporting structure. As shown in Fig. 4, the paraboloid 2 is constructed of a series of layers of glass cloth or "Fiberglass" sheets 10 to form resin-impregnated, supporting sheets as will be further described below. Wire screen 11 provides the reflector. The support 9 is surrounded by a foam plastic 12 (such as alkyd-isocyanate available, e.g., under the trade name "Lockfoam" as manufactured by Napco Chemical Company of Harrison, New Jersey). A portion of the foam plastic has been cut away to expose the support 9.

In Fig. 5 the support rod 4 is shown assembled to the metallic support 9. An extension of the support 9 is counterbored at 13 and a hole drilled and tapped at 14, larger than the outer diameter of the support rod. The support rod is threaded as at 15 and inserted into the oversized hole. A round nut 16 is threaded on to the support rod 4. An epoxy resin 19, such as Hysol 6020 as manufactured by Houghton Laboratories, Inc., of Olean, New York, is poured into the space provided between the support rod 4 and the support 9. The mounting nut 16 is counter-bored and drilled to permit insertion of the set screws 17 into the threaded holes 18 in the support 9. The use of this technique for securing the support rods precludes distortion of the paraboloid and enables the radiator to be assembled very accurately on the axis of the paraboloid.

The paraboloid is assembled in a three-step molding process. The inside laminate of the paraboloid is formed by means of a vacuum bag technique on the surface of the convex part of the mold. Two sheets of glass cloth 10 are placed on the convex mold piece, covered by a sheet of wire screening 11 and followed by another sheet of glass cloth 10, and laminated together with the use of an alkyd polyester resin commercially available as Selectron 5003 as manufactured by Pittsburgh Plate Glass Company, Pittsburgh, Pennsylvania. The outside laminate is formed on the concave portion of the mold and consists of two glass cloth sheets 10 laminated together with the alkyd polyester resin. The support 9 is placed on the concave mold and the foaming resin is poured in and the mold is closed. After a suitable curing period, the mold is opened and the paraboloid removed. The use of poly-tetra-fluoro-ethylene, available under the trade name of "Teflon" as manufactured by E. I. du Pont de Nemours & Company, covering the surfaces of the mold and operating as a mold release permits ready removal of the paraboloid.

A number of techniques are available for providing a conductive reflecting surface. In addition to the use of screen wire, a conductive coating may be electroplated on a desired surface or condensed from a saturated atmosphere.

The antenna embodying this invention is of light weight, sturdy construction and can be manufactured with great facility and economy.

While there has been hereinbefore described what is at present considered a preferred embodiment of the invention, it will be apparent that many and various changes and modifications may be made with respect to the embodiment illustrated without departing from the spirit of the invention. It will be understood, therefore, that all those changes and modifications as fall fairly within the scope of the present invention, as defined in the appended claims, are to be considered as a part of the present invention.

What is claimed is:

1. A composite parabolic antenna comprising in combination successive parabolic layers of resin-impregnated,

glass cloth; a parabolic conductive reflecting member; a metallic supporting web adapted to carry an antenna and having a substantial part thereof disposed between said layers of glass cloth and behind said reflecting member; a foam resin binding together said layers of glass cloth, said reflecting member and said metallic web to form a composite parabolic reflector; a radiator secured to and accurately centered by said metallic web; and a plurality of supporting rods mechanically connecting said radiator to said metallic web.

2. A composite parabolic antenna comprising in combination successive parabolic layers of resin-impregnated, glass cloth; a parabolic conductive reflecting member; a metallic supporting web member carrying an antenna radiator; a foam resin binding together said layers of glass cloth, said reflecting member and said metallic web member to form an integral one-piece parabolic reflector; a plurality of radiator supporting rods connected to and extending from said radiator to said metallic web member; and plastic means joining said rods and said metallic web.

3. A composite parabolic antenna comprising in combination successive parabolic layers of resin-impregnated, glass cloth; a parabolic conductive reflecting member; a metallic supporting web having an annular central part adapted to receive an antenna radiator with quadrantly disposed members extending therefrom and integrally formed therewith and adapted to receive radiator support rods, said extension members and a substantial part of said annular central part being disposed between said layers of glass cloth and behind said reflecting member; a foam resin binding together said layers of glass cloth, said reflecting member and said metallic web to form a composite parabolic reflector; a radiator secured to said central part and accurately centered by said metallic web; 35

four supporting rods mechanically connecting said radiator to said members, each of said rods extending through over-size threaded orifices in its respective extension member and having a threaded portion within said orifices; a threaded retainer having an outer diameter greater than the diameter of said orifices secured to the threaded portions of each of said rods; and a plastic resin securing said rod and retainer to said web to enable strain-free assembly of said rods to said web without further adjustment.

4. A composite parabolic antenna reflector, comprising, in combination: successive parabolic layers of resin-impregnated, glass cloth; a parabolic, metallic screen reflecting member; a generally concave, metallic, supporting web, having an annular central part adapted to receive an antenna device with quadrantly disposed members extending therefrom and integrally formed therewith and adapted to receive said quadrantly disposed members of said antenna device, said web and a substantial part of the annular central part thereof being disposed between said layers of said glass cloth and behind said metallic screen reflecting member; and a foam resin binding together said layers of glass cloth, said reflecting member and said metallic web to form said composite reflector.
